BOTTLE ARRANGING MACHINE

Kaye B. Holstebroe, Gildersleeve, and Ludwig Wimmer, Middletown, Conn., assignors, by mesne assignments, to Emhart Manufacturing Company, a corporation of Delaware

Original application November 4, 1942, Serial No. 464,444, now Patent No. 2,452,376, dated October 26, 1948. Divided and this application January 21, 1948, Serial No. 3,604

4 Claims. (Cl. 198—34)

1

This invention relates to article handling or arranging apparatus for articles such as bottles, cans and like containers and other round or rounded articles capable of standing in upright position. More particularly the invention relates to apparatus for arranging such articles in successive rows each containing a predetermined number of the articles uniformly spaced apart from one another ready to be discharged into a shipping case, or into apparatus for performing a further operation on the articles or their contents, such for example, as baking, coating, annealing, cooking apparatus, etc.

The general object of the present invention is to provide an improved row forming mechanism that is smooth and reliable in its operation, which is entirely automatic and does not require the presence of an attendant.

Another object of the invention is to provide a row forming mechanism which will operate on fragile articles, such as bottles, with a minimum of breakage.

The invention also aims to provide a row forming mechanism which effects positive separation and positive maintenance of the spacing of the articles.

Although the row forming mechanism of the present invention is capable of general use, as indicated above, the invention will be described in connection with an apparatus for packing bottles in cases or trays wherein the bottles are received in individual compartments or cells formed by partitions placed at right angles to one another, such shipping cases being referred to in the trade as cell-cases. In this apparatus the bottles are inserted one row at a time, this application being a division of our copending application S. N. 464,444, filed November 4, 1942, now Patent No. 2,452,376.

In packing machines of this kind, which are known as single row packers, considerable difficulty has heretofore been experienced in arranging the bottles of each row in suitably spaced relation to one another so that their insertion in the case may proceed without jamming of the articles on the edges of the cell partitions, and one of the specific objects of the invention is to overcome this difficulty.

An embodiment of the invention is illustrated by way of example in the accompanying drawings and the invention will be understood from a consideration of these drawings taken together with the following description. In the embodiment of the invention illustrated the machine is arranged to place well known beverage bottles in

2

wooden trays having both longitudinal and cross partitions forming the cells for the individual bottles. These trays are of less height than the bottles and are used in the distribution of the product to the retail trade. It will be understood, however, that the apparatus of the invention may be employed for filling shipping cases of greater height than the bottles and constructed of any suitable material, and also that the trays illustrated may be made of any suitable material.

In these drawings:

Fig. 1 is a plan view of a portion of a bottle packing machine embodying the row forming mechanism of the invention;

Fig. 2 is a view in longitudinal section taken on line 2—2 of Fig. 1;

Fig. 3 is a transverse vertical section taken on line 3—3 of Fig. 1 with the cans and certain parts omitted;

Fig. 4 is a longitudinal vertical section taken on line 4—4 of Fig. 1 drawn to an enlarged scale;

Fig. 5 is a view similar to Fig. 4 but showing the parts in a different position;

Fig. 6 is a view showing the driving mechanism of the flight chain;

Fig. 7 is a fragmentary view showing certain parts of Fig. 6 in a different position, and

Fig. 8 is a diagram of electrical connections.

Referring now to the accompanying drawings, the bottles to be packed come in from the right hand side of the machine, as viewed in Fig. 1 (the front end of the machine being at the left), on an endless supply conveyor indicated generally by numeral 1. The cell trays are advanced through the machine on a second endless belt conveyor indicated generally by numeral 2 at right angles to the bottle conveyor 1 and moving from the rear of the machine toward the opposite or front end. The trays are supplied to conveyor 2 by means of a supply conveyor, not shown, which may be, for example, of the gravity roller conveyor type, and if desired may come down from a floor above.

The filled trays leaving conveyor 2 at the front end of the machine (at the left in Fig. 1) are received by a delivery conveyor 3 which is shown as being of the roller gravity operated type.

The bottle conveyor 1 is above the tray conveyor 2 and delivers the bottles to a row-forming mechanism indicated generally by numeral 4 which is in line with conveyor 1. By means of this mechanism the bottles are arranged in rows of six bottles each spaced apart from one another to correspond with the thickness of the tray partitions, such rows being successively formed and

deposited by gravity in the respective compartment rows of each case.

The tray conveyor comprises two endless plat-form chains 2 arranged parallel to one another to support the opposite sides of the trays. Chains 2 are carried by sprockets 5 on a driving shaft 6 at the front end of the machine and by similar sprockets on an idler shaft (not shown) at the rear. These shafts are journaled in horizontal side frame members 9 and 10. Appropriate side guides for the sides of the trays are provided to keep the trays lined up on conveyor chains 2 and in registry with the row-forming mechanism 4. Conveyor chains 2 are maintained horizontal by means of two supporting bars 11 (Fig. 3) extending longitudinally of the machine, and a supporting bed or plate 12 (Fig. 6) is provided between the chains for the trays.

The bottles are deposited in the trays by mechanism which is actuated by a number of cams, most of which are carried on a cam shaft 13 extending crosswise of the machine between frame members 9 and 10. This mechanism will be referred to again later on. The machine is driven through a chain 18 which is trained around a sprocket 20 on cam shaft 13 (Fig. 3) and also around a sprocket 21 (Fig. 1) on driving shaft 6 of the tray conveyor. Power is supplied to chain 18 from a motor and speed reducing gear box not shown.

Bottle conveyor 1 is supported by a driving sprocket 24 (Fig. 1) and an idler sprocket (not shown). Shaft 25 on which driving sprocket 24 is mounted has at its left end another sprocket 26 which is driven through a chain 29 from a sprocket on the right end of a short shaft 28 located below shaft 25. Shaft 28 is driven through beveled gearing 27 from shaft 6 of the tray conveyor. Through these connections both bottle conveyor 1 and tray conveyor 2 are driven continuously.

The bottle row-forming mechanism 4 comprises a series of equally spaced plates or flights 31 carried by a pair of endless chains 32 and 33 arranged one above the other (Fig. 4). This device as a whole will be referred to as the "flight chain." Chains 32 and 33 of this device are carried by two pairs of sprockets 34 and 35 all of the same diameter. The pair of sprockets 35 are mounted to rotate on an upright stub shaft 36 which is fixed between two horizontal frame plates 37 and 37a on the left hand side of the machine (Fig. 3). The pair of sprockets 34 are keyed to a short rotatable shaft 38 journaled on the right side of the machine between frame plates 37 and 37b. The purpose of having shaft 38 driven by the flight chain will appear later. Frame plate 37 extends from side to side of the machine whereas plates 37a and 37b are short plates mounted in fixed relation to plate 37 at its opposite ends.

As may be seen from Fig. 4 the two chains 32 and 33 constituting the flight chain are each arranged to move between closely fitting horizontal guide bars 39. These extend between the two pairs of sprockets 34 and 35. These guide bars coact with the rollers of the chains to maintain the plates or flights 31 in vertical position, these flights each being secured to a bracket 40 and each of these brackets being carried on pins 41 each of these brackets being carried on pins 41 (Figs. 4 and 6) extending between the two chains 32 and 33. The base of each bracket 40 is secured to two adjacent pins 41 so as to firmly support flights 31 at right angles to the two chains.

These flight plates 31 have a thickness corresponding to the thickness of the partitions in the trays and hence hold adjacent bottles in properly spaced relation to be received by the tray. In order to position the bottles laterally on the side towards the chains 32 and 33 each of brackets 40 carries a back plate 42 which is mounted at right angles to the flight plates 31. Hence along the straight portions of the flight chain between the two pairs of supporting sprockets 34 and 35, a series of pockets is formed one between each adjacent pair of flight plates 31. The bottles in these pockets are spaced apart by the thickness of plates 31. By properly controlling the movement and stopping of the flight chain, these plates 31 may be positioned vertically above the tray partitions so that the pockets between the flights will be in registry with the cells or compartments of the row of the case beneath when this case has been fed forward to its receiving position, as will be described below.

The bottles in the row to be deposited in the tray are held in the pockets just referred to by means of a vertically shiftable apron 43 (Figs. 1, 4 and 5) which serves to guide and position the front sides of the six bottles in this row. Apron 43 is shifted downwardly by appropriate mechanism, and at the proper time, until its lower edge rests upon the front wall of the tray or upon one of the cross partitions so as to guide the fronts of the bottles to prevent them from being caught on the upper edges of these members.

The six bottles forming the row are supported on a shutter plate 44, (Figs. 3, 4 and 5), the upper surface of which is at the same level as the top of frame plate 37 and which is arranged to be withdrawn laterally to the right as shown in Fig. 4 to allow the bottles to drop toward the tray at the proper time. Shutter plate 44 is secured to a support consisting of a cross bar 45 (Fig. 4) having at its opposite ends legs 46 which are slidable on rabbeted members 47, which are fastened to the lower side of frame plate 37. A rear cross bar 48 (Fig. 4) serves to tie together the rear ends of legs 46.

To actuate the shutter plate support just described, links 49 (Figs. 1, 4 and 5) are pivoted to the rear ends of legs 46 and connected to arms 50 which are pinned onto a cross shaft 51. On the left hand end of this shaft there is an actuating arm 52 carrying a roller 53 which engages a cam 54 on another cross shaft 55. This cross shaft is driven from main cam shaft 13 by means of a chain 56 and sprockets of equal size (Figs. 2 and 5). Hence shaft 55 rotates continuously at the same speed as main cam shaft 13.

The flight chain (chains 32 and 33) carrying the flight plates 31 is actuated to feed in bottles from the flight conveyor 1 to form successive rows by mechanism which is driven from cross shaft 55. This mechanism consists of a continuously reciprocating carriage 57 which is arranged to travel on a square slide bar 58 mounted above frame plate 37 inside of the flight chain. Carriage 57 has pivoted to it a ratchet mechanism which may connect the carriage with the chain at the commencement of each forward stroke so that the chain may be advanced a distance corresponding to the length of a row of six bottles at each stroke of carriage 57. This ratchet mechanism includes upper and lower ratchets 59 (Figs. 4 and 6) which are provided with hook portions to engage roller pins 60 on chains 32 and 33.

These pins on chain 32 extend upwardly and those on chain 33 extend downwardly. They are spaced apart on the two chains a distance corresponding to six bottle pockets. The two ratchet members 59 each have hubs extending respectively above and below carriage 57 and these hubs are pinned as shown in Fig. 4 to a common shaft 61 to cause both ratchets to move in unison so that the lower ratchet 59 can be controlled by movement of the upper ratchet in a manner to be described later on for the purpose of interrupting the advance of the flight chain under certain conditions.

Reciprocating carriage 57 is moved back and forth by means of an actuating arm 62 pivoted at its rear end to a short link 63 which in turn is pivoted to the frame of the machine so as to allow carriage 57 to move in a straight line on its supporting bar 58. Actuating arm 62 is driven by means of a connecting rod 64 operated by a crank 66 (Fig. 1) which rotates in a horizontal plane being fixed upon the upper end of a short vertical shaft 67 which rotates in a bracket secured to the left side of the machine. Shaft 67 is driven through beveled gearing 68 from continuously rotating cross shaft 55.

The bottles arrive at the packing machine on supply conveyor 1 and are to be spaced apart to correspond with the thickness of the cell-case partitions, and arranged in rows. The mechanism of the present machine simultaneously spaces the bottles apart and advances them in spaced relation and in single row formation from conveyor 1 to a discharge position immediately above the cell-case. To assist in causing the bottles from conveyor 1 to enter each of the spaces between adjacent pairs of flight plates 31, a star wheel 69 is provided (Fig. 1). This star wheel preferably comprises upper and lower sections, the upper section being shown in Fig. 1 and the lower section being in registry with the upper. Their hubs are pinned to a vertical shaft 70 which is supported for rotation at the outer end of a bracket 71. Bracket 71 is secured to one of two upright posts 72 one on each side of the machine. Shaft 70 is operatively connected with shaft 38 of sprockets 34 at the right hand end of the flight chain.

For this purpose a pair of spur gears 73 are used in order to obtain the correct direction of rotation of the star wheel, one of these gears being fixed to the upper end of shaft 38 and the other rotating on a short stationary shaft 74 which extends upwardly from frame plate 37a. Also rotating on shaft 74 just above gear 73 and connected thereto there is a sprocket 75 which through a chain 76 drives a sprocket on the upper end of shaft 70.

In this way, whenever the flight chain (chains 32 and 33) is advanced from right to left in Fig. 1 by the reciprocation of ratchet carriage 57, the teeth of the star wheel 69 are rotated in timed relation with the movement of the ends of the flight plates 31 as shown in Fig. 1. The bottles are continuously fed forward by the continuously driven conveyor chain 1, the end of which is to the left of the star wheel 69 as shown in Fig. 1. Hence the bottles are continuously urged into the respective pockets of star wheel 69 and as the teeth of the star wheel rotate they force themselves between adjacent bottles and separate them from one another, as shown in Fig. 1, by a distance which is at least equal to the thickness of flight plates 31. The edges of these plates present themselves successively opposite the ends

of the star wheel teeth and maintain the separation of adjacent bottles which has been effected by the star wheel.

Conveyor belt 1 continues to feed the bottles forward as shown in Fig. 1 until the flight plates 31 have rounded sprockets 34 and come into parallel relationship with one another. From this point on the bottles are advanced by the flight chain pockets formed by plates 31 and the other parts previously described. The bottles are guided at their front sides by means of a stationary plate 77 (Fig. 1) which is in alignment with apron 43 until they reach the apron. The bottles are supported on a scuff plate 78 (Fig. 3) after they pass from conveyor chain 1 until they reach the shutter plate 44.

In order to control the advance of the flight chain by reciprocating ratchet carriage 57, the solenoid mechanism and connected parts shown in Fig. 3, 4 and 6-8 is provided. It will be remembered that both the lower and upper ratchets 59 are pinned to their pivot shaft 61 so that the movement of the lower ratchet can be controlled by that of the upper. Upper ratchet 59 is provided with a compression spring 79 which biases the two ratchets to cause their hooks to engage pins 60 on flight chains 32 and 33. On the back stroke of carrier 57, therefore, the hooks of ratchets 59 will snap over pins 60 under the biasing action of spring 79 unless this engagement is prevented.

To retract ratchets 59 to prevent their engagement with pins 60 when it is desired to allow flight chains 32 and 33 to remain stationary, the head of the upper ratchet 59 is provided with a cam surface 80. Cam 80 is engaged by a vertically shiftable pin 81 (Fig. 4) when this pin is shifted to its lower position by the energization of solenoid coil 82. Pin 81 projects downwardly from the left hand end of a lever 83 which is pivoted at 84 and connected to the solenoid plunger through the link 85. When solenoid 82 is de-energized pin 81 is in its upper position shown in Fig. 4 and is out of the path of the upper latch 59. In Fig. 7 pin 81 has been shifted downwardly by the energizing of coil 82 into the path of ratchet 59, and cam surface 80 of this member has engaged pin 81 which has resulted in swinging both members 59 away from the flight chains on the back stroke of carriage 57. It is clear from Fig. 7 that on the next forward stroke, cam 80 will hold the hooks of the ratchets from picking up the chain pins 60. So long as solenoid 82 is energized this action will occur at the end of each back stroke of carriage 57 and consequently the flight chains 32 and 33 will remain stationary.

One of the conditions under which it is desired to leave flight chains 32 and 33 stationary is upon the failure of the supply of bottles on conveyor 1; another is upon the failure of the supply of empty cases on conveyor 2. Devices are provided for energizing solenoid 82 under either of these conditions, but only the mechanism operative in response to failure of the bottle supply is disclosed herein. Reference to applicants' prior application above mentioned may be had for a description of the case operated mechanism.

Referring to the circuit diagram (Fig. 8) switch 86 is controlled by the bottles and so long as the line of bottles on conveyor 1 is maintained the contacts of switch 86 are held open, but should the bottle supply line fail, these contacts will be closed, thereby closing a circuit through solenoid

82 from supply conductors 86 and preventing the advance of flight chains 32 and 33.

The contacts of bottle-actuated switch 86 are separated by means of an actuating rod 91 which is biased toward the row of bottles by a helical spring 92. Rod 91 is provided with a shoe 93 (Fig. 1) which engages a single bottle which is shifted laterally of the line of bottles on conveyor 1 by means of a cam guide block 94. Cam block 94 serves to shift the bottle opposite it out of the line and this bottle is then squeezed further out by the pressure of the bottles immediately in front and behind it.

The advance of the trays or cases from the rear of the machine toward the front, that is to say, from right to left in Figs. 4 and 5, for example, in a step-by-step movement is controlled by means of mechanism shown in these figures and in Figs. 2 and 3. This mechanism causes the cases to be advanced one row at a time and has alternately shiftable fingers 100 and 101. These two sets of fingers are so interconnected that when one set is shifted upwardly the other is simultaneously shifted downwardly after the manner of an escapement mechanism. The set of fingers 100 comprises a pair of rigid fingers for each bottle compartment of the row to be packed (Fig. 2). Fingers 100 are maintained always vertical by means of a parallel motion mechanism. For this purpose these fingers are mounted upon a vertically movable carrier 102. Carrier 102 has at each end vertical legs which are pivoted to two sets of equal length supporting arms 103 and 104. The lower arms 104 are pivoted loosely on rotating main cam shaft 13. Arms 103 above are pinned to an actuating rock shaft 105 which is parallel to shaft 13 and pivoted in the frame of the machine vertically above it.

Finger 101 of the escapement mechanism is pivoted at 106 to a fixed part of the machine and is actuated by an extension 107 at the rear of pivot 106 which is connected through link 108 to a short arm 109 on the forward side of rock shaft 105. By this mechanism when shaft 105 is rocked in one direction, fingers 100 move downwardly and finger 101 moves upwardly, and vice versa, when shaft 105 is rocked in the opposite direction.

Rock shaft 105 is actuated by a cam 110 at the left hand end of main cam shaft 13 (Fig. 2) but is permitted to move only when an arm 111 is released by a latch mechanism. This mechanism is not described in this specification but is set forth in detail in the prior application above mentioned. By means of this mechanism the feeding forward of the tray is permitted only if the flight chain has brought a row of bottles into position ready to be deposited in the tray. Otherwise the tray might be fed forward out of the machine with one or more rows empty.

Because of the latching of rock shaft 105 against movement, as described above, the arm 114 (which has a roller 115 engaged by escapement actuating cam 110) is mounted loosely on rock shaft 105 and its motion is transmitted thereto by a yieldable connection shown in Fig. 2 and indicated generally by numeral 119.

The sequence of operations in feeding a tray into position to receive a row of bottles and causing the row to be deposited in the tray cells can be understood from Figs. 4 and 5. The drag of the continuously moving tray conveyor chains 2 urges the trays to the left and the foremost tray is stopped by the engagement of fingers 100 with the front thereof (Fig. 2). A row of bottles is in position between flight plates 31 of the flight

chain and supported on shutter plate 44. The lobe of cam 110 is about to move roller 115 outwardly, and it will be understood, that the latch mechanism referred to has been actuated to release arm 111 so that the outward movement of roller 115 is about to cause the rocking of shaft 105.

In Fig. 4 rock shaft 105 has been rocked by the movement of the lobe of cam 110 beneath roller 115 to lift fingers 100 and lower finger 101 and the conveyor has carried the case forward until the front of the first partition has engaged the rear of finger 101, thus arresting the movement of the case.

In Fig. 5 cam 110 and shutter plate cam 54 have rotated a slight distance farther, the lobe of cam 110 just passing beneath roller 115. This has caused the position of the escapement fingers 100 and 101 to be restored to their former position, resulting in the advance of the case to bottle-receiving position with its front row of cells accurately positioned beneath the row of bottles on shutter plate 44, being held by fingers 100.

In Fig. 5 shutter plate cam 54, through the operating mechanism previously described, has withdrawn shutter plate 44 to a point where it is just about ready to release the row of bottles, and in another instant such release will have taken place and the bottles will have descended into the tray.

Although our invention has been described as embodied in a machine for packing bottles it will be understood that, as mentioned at the beginning, it can also be used for packing cans or other similar articles. Accordingly, the term "bottle" as used in the appended claims is intended to include other articles such as those mentioned.

In our improved bottle packing apparatus we have provided a machine which is quiet, rapid and automatic in operation. It will be understood, however, that changes may be made in the arrangement and construction of the apparatus as herein described as well as in the details of such apparatus without departing from our invention, the scope of which is indicated in the appended claims.

We claim:

1. In apparatus of the class described, bottle row-forming mechanism comprising an endless chain having flights thereon spaced apart by the diameter of the bottles, sprockets for supporting a portion of said chain in a straight line to form a row containing a predetermined number of bottles, a bottle feed line conveyor arranged to deliver bottles between the successive flights of said chain, a reciprocating carriage disposed adjacent a straight portion of said chain, means for reciprocating said carriage with a stroke whose length corresponds to the number of bottles in the row to be formed, a ratchet member pivoted on the carriage, driving lugs on said chain, said ratchet member being biased to engage one of said lugs as the carriage approaches the end of its back stroke to advance the chain on the next forward stroke of the carriage, and means for controlling the actuation of said chain by said carriage comprising mechanism for retracting said ratchet and holding it out of engagement with said lug during commencement of said forward stroke.

2. In apparatus of the class described, bottle row forming mechanism comprising an endless chain having flights thereon having vertical edges

and spaced apart by the diameter of the bottles, sprockets for supporting a portion of said chain in a straight line to form a row containing a predetermined number of bottles, a conveyor for a bottle feed line having bottles in close formation and extending in approximately the same plane as said chain, a star wheel disposed on the opposite side of the bottle line from said sprockets, said star wheel having teeth the ends of which are constructed and arranged to coact with the vertical edges of said flights as they move around one of said sprockets, means for operatively interconnecting said chain and star wheel to cause said teeth to move in unison with said flights to space the bottles apart and place them between 15 said flights, and mechanism for intermittently driving said chain to form successive rows of bottles.

3. In apparatus of the class described, mechanism for forming successive rows of a predetermined uniform number of bottles comprising an endless chain having flights thereon having vertical edges and spaced apart by the diameter of the bottles, sprockets for supporting a portion 20 of said chain in a straight line to form a row containing said number of bottles, a conveyor for a bottle feed line having bottles in close formation and extending in approximately the same plane as said chain, a star wheel disposed on the opposite side of the bottle line from said sprockets, 25 said star wheel having teeth the ends of which are constructed and arranged to coact with the vertical edges of said flights as they move around one of said sprockets to space the bottles apart 30

and place them between said flights, a reciprocating carriage whose stroke corresponds to the number of bottles in each row to be formed, a coupling device on said carriage to drive said chain, and means for controlling said coupling device to cause formation of successive rows of bottles.

4. Apparatus of the class described as set forth in claim 1 in which the mechanism for retracting and holding the ratchet member out of engagement with the driving lugs includes a cam on the ratchet member, a laterally shiftable cam-engaging member positioned in the path of said cam, and means for shifting said cam-engaging member into and out of said path.
